SMOKING PIPE

Edgar E. Lancaster, Cleveland, Ohio

Application August 23, 1949, Serial No. 111,822

1. Claim. (Cl. 131—191)

1

This invention relates to improvement in tobacco pipes and more particularly to a pipe which cools and filters the smoke passing therethrough, which is easily cleaned, is shaped for convenience in carrying, is rigid in construction, and is economical to produce.

Other objects and advantages will be apparent from the drawings which illustrate a preferred embodiment of the invention and in which:

Fig. 1 is a horizontal plan view of the pipe embodying the principles of the present invention;

Fig. 2 is a longitudinal sectional view taken on the line 2—2 of Fig. 1; and

Fig. 3 is a left end elevation of the pipe illustrated in Fig. 1.

The present pipe is one in which one of the most important features is a one-piece barrel of compacted metal arranged with straight through and easily cleaned passages so as to cause the smoke to pass through a restricted duct which causes intimate contact between all portions of the smoke and the wall of the duct, the heat being removed from the duct wall by metal conduction of a large mass of metal which is capable of removing the heat so rapidly between intermittent draughts of smoke that the duct wall is cool for each succeeding draught and which, in turn, more slowly radiates the heat into the air from the large mass of metal by radiating fins, and a filter for absorbing the condensate resulting from the rapid cooling.

The pipe comprises essentially a cylindrical barrel, indicated generally at 1, formed from a single piece of compacted metal, such as aluminum or steel bar or rod stock. The barrel is bored to provide a thin walled enlarged bowl receiving bore 2 which is adapted to receive a wooden tobacco supporting bowl 3, the bowl 3 being press fitted into the bore 2 and additionally secured in place by a press fitted annular washer 4. The bowl 3 is shaped externally so as to fit the bore 2 so that no cavities exist between the walls of the bowl and bore.

At its inner end the bore 2 is connected to one end of a duct 5 which at its opposite end is connected to a filter bore 6 which opens through the other end of the barrel 1. The bowl 3 has in its base or inner end the usual port which is coaxial with and forms in effect a continuation of the duct 5.

The end of the barrel opposite from the bore 2 is provided with a reduced diameter portion 7, and adjacent thereto a larger diameter portion 8, the portions 7 and 8 receiving with a press fit a suitable mouthpiece 9.

2

The mouthpiece 9 is formed of amber, hard rubber, or one of the synthetic plastics. It is provided with the usual axial duct and with internal bores adapted to receive the portions 7 and 8 with a tight slip fit so as to be readily detachable for cleaning. A small ferrule 10 preferably is provided at the inner end of the mouthpiece 9 for reinforcing the relatively thin walls there existing.

Fig. 1 is a horizontal plan view of the pipe embodying the principles of the present invention;

Fig. 2 is a longitudinal sectional view taken on the line 2—2 of Fig. 1; and

Fig. 3 is a left end elevation of the pipe illustrated in Fig. 1.

The present pipe is one in which one of the most important features is a one-piece barrel of compacted metal arranged with straight through and easily cleaned passages so as to cause the smoke to pass through a restricted duct which causes intimate contact between all portions of the smoke and the wall of the duct, the heat being removed from the duct wall by metal conduction of a large mass of metal which is capable of removing the heat so rapidly between intermittent draughts of smoke that the duct wall is cool for each succeeding draught and which, in turn, more slowly radiates the heat into the air from the large mass of metal by radiating fins, and a filter for absorbing the condensate resulting from the rapid cooling.

The pipe comprises essentially a cylindrical barrel, indicated generally at 1, formed from a single piece of compacted metal, such as aluminum or steel bar or rod stock. The barrel is bored to provide a thin walled enlarged bowl receiving bore 2 which is adapted to receive a wooden tobacco supporting bowl 3, the bowl 3 being press fitted into the bore 2 and additionally secured in place by a press fitted annular washer 4. The bowl 3 is shaped externally so as to fit the bore 2 so that no cavities exist between the walls of the bowl and bore.

At its inner end the bore 2 is connected to one end of a duct 5 which at its opposite end is connected to a filter bore 6 which opens through the other end of the barrel 1. The bowl 3 has in its base or inner end the usual port which is coaxial with and forms in effect a continuation of the duct 5.

The mouthpiece 9 is formed of amber, hard rubber, or one of the synthetic plastics. It is provided with the usual axial duct and with internal bores adapted to receive the portions 7 and 8 with a tight slip fit so as to be readily detachable for cleaning. A small ferrule 10 preferably is provided at the inner end of the mouthpiece 9 for reinforcing the relatively thin walls there existing.

The external surface of the barrel, between the portion 7 and the opposite end, is provided with a plurality of radial flanges 11. The bore 2, duct 5 and bore 6 are coaxial and are about equal in length. The bore 2 is relatively large and thin walled whereas the duct 5 is relatively small. The bore 6 is much larger than the duct 5 and preferably is large enough in diameter and of the proper length to accommodate snugly one-half of an ordinary cigarette 12 which serves as a removable filter medium.

The barrel, taken to the outer dimensions of the fins 11, is generally cylindrical though it may be slightly greater in diameter near the longitudinal mid-portion with a slight taper toward the ends. The portion of the barrel between the inner end of the bore 2 and the outer end of the bore 6 is such that the defining wall of the duct 5 is relatively very thick, the radial thickness, exclusive of the fins 11, preferably being more than one-half the diameter of the fins 11 at that portion so as to provide an effective heat absorbing and radiating means 13 for absorbing heat from the smoke and for dissipating it rapidly into the air.

A distinct advantage results from such an extremely thick wall and small duct in the heat absorbing and radiating means 13. A relatively small duct is necessary in order to assure that all of the smoke passes into intimate heat exchange relationship or contact with the walls of the duct. Such a small duct, however, has a very small exposed wall surface. This results in a very rapid rate of heat exchange between the smoke and the metal wall of the duct 5.

The radiation of heat from metal into air is much slower than the conduction of heat from one portion of a piece of metal to another. Therefore, a large mass of metal is provided to conduct the heat from the relatively small exposed wall surface area of the duct 5 rapidly so that the smoke subsequently drawn through the duct can be cooled by the same small wall surface area of the duct. Having withdrawn the heat from the exposed surface area of the wall of the duct 5 rapidly, the heat is conducted to a

large radiating area which though radiating more slowly per unit area has a much larger surface area than could be provided directly for the small diameter duct. Since the fins are integral with the barrel, conduction into them from the large mass of metal is relatively rapid.

Very rapid chilling of the smoke occurs in its short passage through the duct 5. Such rapid chilling necessarily results in the formation of condensation which is readily carried into the filter bore 6. Accordingly it is necessary because of the high rate of formation of condensation to provide the absorbing filter such as the cigarette 12.

Since the bowl 3 is generally of wood its heat conducting properties are considerably less than that of the metal barrel, and the limited amount of heat conducted to its outer surface can be dissipated readily by metal conduction through the relatively thin metal wall defining the bore 2 and radiated by the relatively small fins on the barrel adjacent and surrounding that portion in which the bore 2 is formed.

By making the bowl receiving portion of the barrel, the heat exchange portion, and the portion containing the filter bore 6 integral and providing fins as nearly coextensive with the length thereof as possible, a large amount of metal is provided for rapidly conducting the heat from its point of initial heat exchange so that the wall of the duct 5 is cooled sufficiently between intermittent draughts of smoke therethrough.

Due to the straight through construction of the various bores and ducts the pipe can easily be cleaned. Due to the external construction, it can be readily carried in the pocket. As a result clean, relatively dry and cool smoke is obtained at all times.

Having thus described my invention, I claim:

A smoking pipe including an elongated barrel and a mouthpiece detachably connected to said barrel, said barrel being of relatively high heat conducting material and having a generally cylindrical outline, said barrel having a tobacco bowl receiving bore at its outer end and a filter receiving bore at its inner end and a bowl in said bowl receiving bore, and a cooling portion having a smoke duct therein between said ends, said barrel having radially extending fins spaced therealong for substantially the full length thereof starting from the outer end, the radial extent of the fins and the wall thickness of the barrel being such as to provide a large diameter bowl receiving bore portion having relatively short radial fins, a smaller filter bore portion having greater radial extent fins and said smoke duct having a smaller diameter than either of said bores and having a wall thickness such that the radial fins therearound have substantially the same radial extent as those surrounding the filter bore, said bowl, said barrel and said mouthpiece being coaxial.
